UNITED STATES PATENT OFFICE

165,573

HANDBAG

Herbert S. Chase, New York, N. Y.

Application February 7, 1951, Serial No. 14,133

Term of patent 3½ years

(Cl. D87—3)

To all whom it may concern:

Be it known that I, Herbert S. Chase, a citizen of the United States of America, residing in New York city, county of New York, and State of New York, have invented a new, original, and ornamental Design for a Handbag, of which the following is a specification, reference being had to the accompanying drawing, forming part thereof, wherein:

Figure 1 is a front elevational view of a handbag, showing my new design.

Figure 2 is a rear elevational view of the handbag shown in Figure 1, drawn on a smaller scale.

Figure 3 is a side elevational view of Figure 2.

Figure 4 is a fragmentary front elevational view of the handbag with the flap open, the lower portion of the bag, which is fully shown in Figure 1, being omitted.

The characteristic features of my design reside

in the portions shown in full lines in the drawing.

I claim:

The ornamental design for a handbag, substantially as shown and described.

HERBERT S. CHASE.
